UNITED STATES PATENT OFFICE.

CHRISTIAN T. GUTLEBEN, OF OAKLAND, CALIFORNIA, ASSIGNOR TO GUTLEBEN BROTHERS, OF SAN FRANCISCO, CALIFORNIA, A CORPORATION OF CALIFORNIA.

SAND AND GRAVEL SCREEN.

Application filed July 14, 1922. Serial No. 574,903.

To all whom it may concern:

Be it known that I, CHRISTIAN T. GUTLEBEN, a citizen of the United States, residing at Oakland, in the county of Alameda and 5 State of California, have invented new and useful Improvements in Sand and Gravel Screens, of which the following is a specification.

This invention relates to screening apparatus and particularly to sand, gravel and cobble screens.

It is an object of the present invention to provide a simple, practicable, substantial apparatus of large capacity and comparatively small dimensions for efficiently concurrently separating material into three separate classes. It is specially an object of the invention to provide a screen for the effective separation of river bottom material 20 containing sand, gravel and cobble stone. Another object is to provide an apparatus including a movable carriage adapted to be readily shifted along a pathway so as to form ranges of the screened material, each 25 being entirely separate from the other so as to facilitate the collection and transfer of the material of each pile into convenient vehicles.

Other objects and advantages of the invention will be rendered manifest in the specification of an embodiment of the invention illustrated in the accompanying drawings, in which

Figure 1 is a plan view of the apparatus. 35 Fig. 2 is a side elevation with certain parts being in section.

Fig. 3 is a perspective.

The invention consists of a substantial frame preferably erected in the form of a carriage having parallel side bars 2 and front and rear pairs of supporting legs 3 and 4. The carriage is preferably arranged upon substantial guideways or tracks 5 along which it may be shifted from step 40 to step as accumulations or piles of the material being screened are accumulated to a suitable quantity or volume. In Fig. 2 the carriage is shown as being provided with wheels 6 running upon the tracks 5, while in Fig. 3 the wheels are eliminated 45 and the carriage is provided with longitudinal shoes or runners 7 bearing on the tracks 5. These tracks preferably are in the form of upright planks of substantial dimensions, and these, therefore, form in the

apparatus perpendicular partitions or dividing walls separating the segregate into three ranges along the sides of the tracks.

Pivots mounted at 10 on the carriage side bars 2 is a substantial screen structure 60 consisting of an upper coarse screen 11 and a lower finer screen 12; it being understood that the mesh of the screen may be readily determined according to the size of product being segregated. The upper and lower 65 screen frames are hingedly fastened by side blocks 13 and 14, and to the upper blocks, of which there is one at each side of the upper portion of the frame, there is secured, pivotally, a pair of prop links or braces 15. 70 The upper and lower ends of these braces are perforated at 16 to receive pivot fastenings 17. The lower pivot fastenings pass through the rear overhanging ends of the side bars of the carriage. This provides for 75 the ready angular adjustment of the screens.

The apparatus is erected for use, as for instance upon a gravel bank or river bottom, and the material to be screened is thrown as from the shovel up upon the upper screen 80 11. The oversize material rolls down from the upper screen onto an apron 18 from which the cobbles will collect in piles C which are spaced along the tracks according to the degree of advance of the screens step 85 by step. The material passing through the upper screen 11 engages the lower screen 12, and the eject from this rolls down and falls from the lower end thereof onto a chute 19 discharging in piles of gravel G between the 90 tracks 5. The undersize material passing through the screen 12 falls onto a longer discharge chute 20 which is adjustably connected by links 21 to the bottom screen and the lower end of which is supported as upon 95 a transverse strip 22 on the rear end of the carriage. The chute 20, therefore, discharges the undersize in piles consisting of sands and fine particles S.

It will be seen from the above that the 100 machine is of extreme simplicity and will serve to produce three segregate products, each being arranged in piles to be conveniently removed and which, if desired, may be approximately measured according to the 105 steps at which the carriage may be successively moved along the rails.

Further embodiments, modifications and changes may be resorted to within the spirit of the invention as here claimed.

What is claimed is:

1. A screening apparatus comprising a set of substantially vertically arranged planks forming tracks and also forming partitions for rows of segregates along the tracks, and a frame mounted upon and adjustable along the tracks and carrying a plurality of superimposed, vertically spaced screens which are arranged substantially vertically above the trackway formed by the planks, one of the screens operating to reject the oversize and discharge it beyond one of the track planks, and a lower screen having a discharge end for discharging material into the space between the track planks, and a discharge means extending inwardly and upwardly to receive the material passing through the lower screen and for discharging it beyond the other side of the trackway.
2. A screening apparatus comprising a carriage frame having parallel side bars and front and rear pairs of vertical legs, elongated upright planks forming tracks

along which the legs are slidable to shift the apparatus, a lower inclined screen frame 25 pivoted at its lower end upon the front ends of the side bars, side blocks along the lower frame, an upper screen attached to the blocks, and links adjustably attachable to certain of the blocks and adjustably 30 attachable to the rear ends of the side bars.

3. A screening apparatus comprising a carriage and a track therefor consisting of upright planks forming a bin, and means including a plurality of screens arranged on 35 the carriage for dividing the material being treated into a plurality of segregates, the screens being arranged in superposed inclined position and each having a discharge device for deflecting the material rejected 40 thereon and passing therethrough into separate zones, one on each side of and one between the tracks.

In testimony whereof I have signed my name to this specification.

C. T. GUTLEBEN.
